Int. Cl. D22—07

U.S. Cl. D22—29

FIG. 1 is an isometric view of the front side, one edge, and the bottom of a fishing lure showing my new design;

FIG. 2 is an isometric view of the rear side, the same edge, and the top thereof; and

FIG. 3 is a smaller scale, orthographic view of the same (left) edge, left side, and part of the rear side shown in FIG. 1, the opposite (right) edge and the right side appearing in correspondence with the edge and side shown.

The broken lines shown in FIG. 1 are for illustrative purposes only.

This application comprises a divisional application of pending application Ser. No. D. 15,073 filed Dec. 20, 1968, for fishing lure.

I claim:

The ornamental design for fishing lure, as shown and described.
